UNITED STATES PATENT OFFICE

ALFRED KRUM, OF DUSSELDORF-ELLER, GERMANY, ASSIGNOR TO RHEINISCHE METALLWAAREN- UND MASCHINENFABRIK, OF DUSSELDORF-DERENDRÖF, GERMANY, A CORPORATION OF GERMANY

TRIPOD CARRIAGE FOR MACHINE GUNS

Application filed December 10, 1930, Serial No. 501,385, and in Germany August 21, 1929.

This invention relates to a foldable tripod carriage adapted particularly for light machine guns. The object of the invention is to provide a tripod carriage of low weight which, for the purpose of transporting or conveying, may be converted into a device easily to be carried on the back of a person which, however, on account of its high natural stability offers, in the position 5 of firing, a good bearing for the gun and supports, without great shocks, the recoil on firing.

According to the invention the under carriage consists of a ring of small mass the 15 cross section of which has a great moment of resistance. Said ring is supported by means of legs. Against the circumference of this ring which forms a flange or tire the upper carriage bears by means of a bracket, forming 20 at its front end a bearing for the elevating gear. Preferably the upper carriage is pivotally mounted in a hub connected by means of hollow spokes to the hollow ring. The upper carriage supports the gun in such 25 a manner that it may be adjusted or oscillated in a vertical plane.

In the accompanying drawings the invention is shown by way of example.

Fig. 1 is a side view, partially in section, 30 of the carriage in a firing position; Fig. 2 shows a cross section through the trunnions and Fig. 3 is a plan view of the under carriage the legs of which are folded for transport.

35 The under carriage consists of the hollow ring *a*, carrying the hinged legs *b* which may be telescoped and oscillated about their hinge points from one horizontal position to another one through a range of 180°. By 40 means of clamping levers *b*, the legs may be fixed in any desired position. The ring *a* is provided with a pointing circle graduation and has a hub *a*, which is connected in said ring by means of hollow spokes. The 45 hub *a* receives a pivot pin of the upper carriage *c* which is secured against lifting by a nut *m*. A longitudinal beam *c* of the upper carriage *c* which, for the purpose of lateral adjustment, preferably is provided with a 50 handle *c*, bears, by means of rollers *c*,

against the ring *a* of the under carriage. Mounted in horizontal bearings *c* of the upper carriage *c* are the trunnions *d* of the forwardly projecting gun support *d* in such a manner, that this support may be oscillated through a range of about 5° downward inclination to 90° elevation. The elevation is given to the gun support by means of an elevating machine which consists of a handle *e* hinged to the upper carriage *c* in the bearing *c* and of the pointing gear *e* 55 pivotally connected with the upper carriage *c* and the gun support *d*. The pivot point of the elevating machine *e* at the longitudinal beam *c* of the upper carriage *c* is arranged beyond the front roller guide upon the pointing circle of the under carriage. The rear end of the gun is movably mounted in a slide guide *d* of the gun support *d*. The middle portion of the gun is hinged to the front end 60 of the gun support *d*, a well known recoil brake *g* being interposed at this portion. By means of a handle *d* which may be inserted into the gun support *d* a quick pointing 65 of the gun may be effected by hand after the elevating gear has been disconnected. The front weight of the oscillating parts is 70 hereby balanced by a well known torsional spring mounted in the trunnion casing *c*. The handle *d* may, if desired, be used for the lateral adjustment and the handle *c* of the upper carriage may be dispensed with.

75 When the gun is to be mounted in the gun support, a rear guide member *f* of the gun is inserted into the slide *d*, whereas 80 the gun is connected to the front part of the support *d*, above the recoil brake *g*, by closing the clip *s*. The gun may therefore be mounted and dismounted in the shortest possible time. For the purpose of transporting or conveying, the gun is dismounted and the legs *b* are folded against the ring *a*, so 85 that they bear against this ring as may be seen from Fig. 3. The whole carriage then forms a flat package which, without any 90 difficulty, may be carried by one man upon the back.

95 What I claim is:

1. In a tripod carriage for light machine guns, the combination of an under carriage 100

in the form of a ring provided with legs hinged thereto and foldable flat against same, said ring having a horizontal pointing circle, an upper carriage rotatably and removably mounted on said ring, a gun mounting removably arranged in the upper carriage and capable of vertical elevation; and a recoil brake adapted to take up the longitudinal recoil movement of the gun mounting.

2. In a tripod carriage, in combination an under carriage in form of a ring, a hub, spokes connecting said hub to said ring, an upper carriage supporting a gun and pivotally mounted, by means of a pin, in said hub of said under carriage and telescoping legs supporting said ring-shaped under carriage and hinged to said under carriage in such a manner as to be capable of being oscillated through a range of 180° and of being folded to contact under said carriage.

3. In a tripod carriage, in combination an under carriage in form of a ring, a hub, spokes connecting said hub to said ring, an upper carriage, a gun support swingably arranged in a vertical plane in said upper carriage, a pin on said upper carriage pivotally mounted in said hub of said ring-shaped under carriage and a beam of said upper carriage bearing against said under carriage, said beam carrying at its rear end a handle and forming at its front end a bearing for an elevating gear.

4. In a tripod carriage, in combination an under carriage in form of a ring, a hub, spokes connecting said hub to said ring, an upper carriage, trunnions at opposite sides of said upper carriage, a gun support swingably arranged upon said trunnions, a recoil brake at the front end of said gun support loosely connecting said gun to said gun support, a slide guide at the rear end of said gun support slidably receiving said gun, a pin on said upper carriage pivotally mounted in said hub of said ring-shaped under carriage and a beam of said upper carriage bearing against said under carriage, said beam carrying at its rear end a handle and forming at its front end a bearing for an elevating gear.

5. In a tripod carriage, in combination an under carriage in form of a ring, a hub spokes connecting said hub to said ring, an upper carriage, trunnions at opposite sides of said upper carriage, a gun support swingably arranged upon said trunnions, a recoil brake at the front end of said gun support loosely connecting said gun to said gun support, a slide guide at the rear end of said gun support slidably receiving said gun, a pin on said upper carriage pivotally mounted in said hub of said ring-shaped under carriage, a beam of said upper carriage bearing against said under carriage, said beam carrying at its rear end a handle and forming

at its front end a bearing for an elevating gear and a handle adapted to be inserted in said gun support for oscillating said gun by hand, after said pointing gear has been disconnected.

In testimony whereof I have affixed my signature.

ALFRED KRUM.
